US00D803880S

(12) **United States Design Patent** (10) **Patent No.:** **US D803,880 S**
(45) **Date of Patent:** **** Nov. 28, 2017**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Sascha Höhne**, Hamburg (DE);
Melanie Siemers, Hamburg (DE)

(73) Assignee: **Apple Inc.**, Cupertino, CA (US)

(**) Term: **14 Years**

(21) Appl. No.: **29/515,146**

(22) Filed: **Jan. 20, 2015**

(51) LOC (10) Cl. **14-04**

(52) U.S. Cl.

USPC **D14/492**; D14/491

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines represent a display screen or portion thereof; which forms no part of the claimed design.

1 Claim, 1 Drawing Sheet
